CHARLES P. IAMS AND JULIAN A. RAMSEY, OF WASHINGTON, PENNSYLVANIA.

TROLLEY-POLE.

1,217,946.

Specification of Letters Patent.

Patented Mar. 6, 1917.

Application filed July 15, 1916. Serial No. 109,427.

To all whom it may concern:

Be it known that we, CHARLES P. IAMS and JULIAN A. RAMSEY, citizens of the United States of America, and residents of Washington, county of Washington, and State of Pennsylvania, have invented certain new and useful Improvements in Trolley-Poles, of which the following is a specification.

10 This invention relates broadly to trolleys, and more particularly to a trolley pole structure.

15 The primary object of the invention is to provide a trolley pole of flexible jointed form adapted to maintain the trolley wheel in readily yielding engagement with the trolley wire and to accommodate itself to widely varying elevations of said wire to such an extent as materially lessens the 20 tendency of said wheel to leave the wire.

25 A further object is to provide a device of the character mentioned which is of simple, inexpensive and durable construction and which is but little liable to become out of order.

With these and other objects in view, the invention resides in the features of construction which will hereinafter be described, reference being had to the accompanying drawings, in which—

Figure 1 is a side elevation of the invention; and—

Fig. 2 is a front elevation of the same.

Referring to said drawings, in which like 35 designating characters distinguish like parts throughout the several views—

1 indicates the main body portion of a sectional trolley pole which may be mounted on a car in any appropriate manner. Pivotedly connected to the upper end of said portion 1 is a relatively shorter pole section 2 the upper end of which is adapted for receiving the usual trolley harp 3 carrying the trolley wheel 4.

45 Rigidly carried by, or formed integral with, the body portion 1 adjacent to its upper end is a rearwardly extending arm 5 which is disposed at such an angle with respect to said body portion that it lies approximately in a horizontal position when said body portion occupies its normal inclined position.

55 Pivotedly connected to the pole section 2 adjacent to the upper end thereof is the upper end of a rod or stem 6 which is movably received adjacent to its lower end in a ver-

tically disposed slot or opening 7 provided therefor in the outer end of the arm 5. Encircling said stem 6 is a spiral spring 8 which has its lower end seated upon said arm 5 and its upper end against a fixed abutment, as the collar 9, carried by said stem. An adjusting nut 10 is threaded upon the lower projecting end of the stem 6 whereby the extent of elevation of the pole section 2 65 under the force exerted by the spring 8 is limited.

In its normal position the stem 6 stands in a forwardly inclined position yieldingly supporting the wheel-carrying pole-section 70 2 in a position wherein it is elevated out of alignment with the lower pole section 1, as shown in full lines in Fig. 1. The spring 8 readily yields to the pressure or weight of the trolley wire 11 upon the wheel and the 75 relatively light movable parts carried by the main pole-section 1 swing downward, as indicated in dotted lines in said figure. As is apparent, due to the relative lightness and consequent sensitiveness of the spring, the 80 wheel lightly tracks the trolley wire in rounding curves and instantly accommodates itself to variations in elevation of said wire, all with but little tendency to leave said wire.

What is claimed is—

85 1. A trolley pole comprising a main body portion, a relatively short pole section pivotally connected at one end to the upper end of said body portion, an arm carried by said body portion adjacent to the upper end of the latter and extending rearward therefrom, a spiral spring interposed between said arm and said short pole section whereby the latter is yieldingly supported, and a stem encircled by said spring, said stem 90 being pivotally connected to said pole section and being movable in a substantially vertical direction with respect to said arm. 95

100 2. A trolley pole comprising a main body portion, a relatively short pole section pivotally connected at one end to the upper end of said body portion, an arm carried by said body portion adjacent to the upper end of the latter and extending rearward therefrom, a rod-like stem having its upper end pivotally connected to the upper pole section adjacent to the upper end of the latter and having its lower end freely movable through the outer end of said arm, and a spiral spring encircling said stem and yieldingly supporting said upper pole section. 105

110 3. A trolley pole comprising a main body

portion, a relatively short pole section pivotally connected at one end to the upper end of said body portion, an arm carried by said body portion adjacent to the upper end of the latter and extending rearward therefrom, a rod-like stem having its upper end pivotally connected to the upper pole section adjacent to the upper end of the latter and having its lower end freely movable through the outer end of said arm, an adjusting nut threaded upon the lower end of said stem for limiting the extent of eleva-

tion of said upper pole section, and a spiral spring encircling said stem, said spring being disposed to yieldingly support said upper pole section in elevated position with respect to said arm.

In testimony whereof we affix our signatures in presence of two witnesses.

CHARLES P. JAMS.
JULIAN A. RAMSEY.

Witnesses:

CLYDE C. HEADLEY,
JAMES A. MAGILL.
